UNITED STATES PATENT OFFICE.

ALBERT L. SLAGER, OF SPRINGFIELD, OHIO.

DESIGN FOR AN ANGLE-IRON.

SPECIFICATION forming part of Design No. 26,838, dated March 30, 1897.

Application filed February 5, 1897. Serial No. 622,068. Term of patent 14 years.

To all whom it may concern:

Be it known that I, ALBERT L. SLAGER, a citizen of the United States, residing at Springfield, in the county of Clarke and State of Ohio, have invented and produced a new and original Design for an Angle-Iron, of which the following is a specification, reference being had therein to the accompanying drawing.

My newly-designed angle-iron is of general
10 T-shaped conformation in cross-section and of any desirable length; and the leading features thereof consist in a double-beveled configuration of the outer portion of the cross-bar of the T, forming an obtuse angle, and
15 of a fillet at one side of the point of junction of the said cross-bar with the other portion of the T.

The accompanying drawing, illustrating my invention, is a sectional perspective view
20 showing a length or portion of my newly-designed angle-iron.

In the drawing, A denotes what may be termed the "straight" bar of the T, and B

the "cross-bar" thereof. The opposite sides
a of the straight bar A are parallel with each
25 other, and the inner faces b of the cross-bar are at right angles to the sides of the said straight bar. The outer faces b' of the cross-bar are beveled or sloped slightly both ways from the center thereof, forming an obtuse
30 angle to each other. At one side of the junction of the cross-bar with the straight bar is formed a fillet c, the outer face of which runs at an angle of forty-five degrees, or approximately so, to the adjacent faces of the cross-bar and straight bar.

I claim—

The design for an angle-iron, substantially as shown and described.

In testimony whereof I affix my signature
40 in presence of two witnesses.

ALBERT L. SLAGER.
